STORAGE CASE FOR A MAGNETIC TAPE CASSETTE

Reinhold M. Weiss, Chicago, and T. Michael Dennehey,
La Grange, Ill., assignors to Memorex Corporation

Filed Sept. 14, 1970, Ser. No. 24,968

Term of patent 14 years

Int. Cl. D3—01

U.S. Cl. D87—1

FIG.
1.

FIG. 3.

FIG. 2. FIG. 4.

FIG. 5.

FIG. 6.

FIG. 8.

FIG. 7.

FIG. 1 is a perspective view of a storage case for a magnetic tape cassette showing a new design;

FIG. 2 is a side elevational view thereof, the other side being substantially a mirror image thereof and where in the cross-hatched portions are continuous in the same manner as the cross-hatched portions of FIGS. 1, 6 and 7;

FIG. 3 is a top view thereof;

FIG. 4 is a side view thereof;

FIG. 5 is a bottom view thereof;

FIG. 6 is a perspective view thereof in an open position;

FIG. 7 is a side elevational view thereof, the other side being substantially a mirror image thereof;

FIG. 8 is a top view thereof.

We claim:

The ornamental design for a storage case for a magnetic tape cassette, as shown and described.
